[57] CLAIM

The ornamental design for a steam iron, as shown and described.

DESCRIPTION

FIG. 1 is a top, front and left side perspective view of a steam iron showing our new design;

FIG. 2 is a reduced front elevational view thereof;

FIG. 3 is a right side elevational view thereof;

FIG. 4 is a rear elevational view thereof;

FIG. 5 is a top plan view thereof;

FIG. 6 is a bottom plan view thereof; and

FIG. 7 is a perspective view of a modified form of FIG. 1, the only difference residing in the inclusion of a rectangular indicator light on the lower left side of the heel rest.

The broken line showing of a conventional cord in FIG. 1 is for illustrative purposes only and forms no part of the claimed design.

FIG-7
